UNITED STATES PATENT OFFICE.

JOHN H. HAGOOD, OF FORT SCOTT, KANSAS.

DOOR CONSTRUCTION FOR STOCK CARS.

Application filed October 20, 1924. Serial No. 744,736.

My present invention pertains to doors and door appurtenances for stock cars, and it has for its object to provide a construction including among other elements a gangway 5 door over which stock can walk.

Other objects and practical advantages of the invention will be fully understood from the following description and claim when the same are read in connection with 10 the drawings, accompanying and forming part of this specification, in which:

Figure 1 is a side elevation showing the outer side of a stock car constructed in accordance with the preferred embodiment of 15 my invention.

Figures 2 and 3 are horizontal sections taken in the planes indicated by the lines 2-2 and 3-3, respectively of Figure 1.

Figure 4 is a detail vertical cross-section 20 taken in the plane indicated by the line 4-4 of Figure 1.

Figure 5 is a detail vertical cross-section in the same plane as Figure 4, but with the gangway door placed in an idle position on 25 the floor of the car body.

Figures 6 and 7 are detail perspective views of parts included in my invention and are hereinafter explicitly referred to.

Similar numerals of reference designate 30 corresponding parts in all of the views of the drawings.

The floor of the car body is indicated by the reference numeral 1, and the side wall of the body being designated by 2, and including 35 stiles 3 at opposite sides of a door opening 4. At 5 is my novel gangway door, the major portion of which is preferably of appropriate wood. Bolted at 6 to the lower portion of the outer side of the door 5 is a 40 metallic strap 7, having at its lower edge two barrels 8 integral with the strap and serving for the hinge connection of two open links 9 of rectangular configuration. The opposite bars of the open links 9 are hinged- 45 ly arranged in integral barrels 10 at the outer ends of metallic straps 11 which latter are bolted at 12 or are otherwise fixedly connected to the floor 1. Manifestly, by virtue of the manner just described of connecting the door 5, the said door 5 may be fastened in the upright position shown in 50 Figures 1, 2 and 4, and when released the door 5 can be placed in the position as shown in Figure 5 or can be arranged so as to depend from the door opening 4 and at the outer side of the car. It will also be noted

that the door 5 can be arranged so as to extend laterally outward from the car body and bridge a space between the car body and a loading platform so that stock can 60 pass over the said door in perfect safety.

Bolted or otherwise connected to the door 5 adjacent to the upper edge thereof is a longitudinal metallic strap 13 with eyes or barrels 14, preferably integral, at its ends, 65 and serving for the hinge connection of angular fastening links 15, Figures 1, 3 and 7.

Included in my invention is a novel and useful door fastener. The said fastener construction comprises an upright metallic plate 70

15 appropriately fixed to the face of one stile 3, and a metallic bar 16 having an eye 17 adjacent to one end which receives a loop 18 on the bar 15 for the connection of the bars 15 and 16 in a loose manner as best 75 shown in Figure 6. The bar 15 is preferably bolted to the stile 3 referred to and is equipped with a pin 19 and with spaced staples 20, the pin 19 being adapted to be received in an aperture 21 of the bar 16 and the staples 20 to be received in slots 22 of the bar 16. It will be noticed that the bar 16 is a keeper bar, and that the staples 20 are adapted to receive a pin 23, the said pin 80

23 being connected by a chain link 24 to a staple 25 or the like on the stile 3 referred to. The staples or projections 20 are designed for use in cooperation with one fastening link 15 in securing in closed and working position the door 5, the keeper bar 90 16 being positioned over the fastening link referred to as illustrated. The other fastening link 15 is slotted to receive a staple 26 on the other stile 3, and is detachably secured on the said staple 26 by a pin 27, Figures 1 and 3.

In the preferred embodiment of my invention the staple 26 is carried by the pendent portion of an angular keeper 28 fixed to the face of the last-named stile 3 100 and adapted to guide and receive the lower portion of an upper slidably door 29, the said door 29 being appropriately hung from a longitudinal rail 30 on the car body and being provided at 31 with a loosely connected fastening link, the said link 31 being apertured, as shown in Figure 2, to receive the pin 19 and is adapted to be interposed as shown in Figure 2 between the body plate or bar 15 and the keeper bar 16.

In the practical use of my invention the upper door 29 is moved longitudinally into

and out of closed position, and when closed may be effectively fastened in the manner described.

The door 5, when the car is to be loaded or unloaded, is moved inwardly as far as the links 9 will permit and is positioned on and in parallelism to the floor of the car body or else is permitted to extend laterally outward from the car body. I would also have it understood that when the door 5 is to be closed and fastened, the lower portion of the said door 5 is positioned as far outward as possible.

Notwithstanding the practical advantages of my improved construction it will be noted that the same is simple and inexpensive and at the same time is well adapted to withstand the usage to which structures of corresponding character are ordinarily subjected.

I have entered into a detailed description of the construction and relative arrangement of the parts embraced in the present and preferred embodiment of my invention in order to impart a full, clear and exact understanding of the said embodiment. I do

not desire, however, to be understood as confining myself to the specific construction and relative arrangement of parts, inasmuch as in the future practice of the invention various changes and modifications may be made such as fall within the scope of my invention as defined in my appended claim.

Having described my invention, what I claim and desire to secure by Letters Patent, is:

In a fastening means for a pair of doors comprising a normally vertically secured plate, a loop extending from the upper end thereof, a bar normally depending from said loop to lie parallel with the plate, a pin laterally extending from said plate, a pair of spaced staples also projecting from said plate, and said bar being formed with an opening and also with a pair of spaced slots 40 to receive the pin and staple respectively and said staples being adapted to receive a link 45 of the doors for securing the same between the plate and bar.

In testimony whereof I affix my signature.

JOHN H. HAGOODY.
